MURRAY H. WARREN, OF MEXICO, MEXICO.

APPARATUS FOR REFINING PETROLEUM.

1,110,361.

Specification of Letters Patent. Patented Sept. 15, 1914.

Application filed November 17, 1913. Serial No. 801,375.

To all whom it may concern:

Be it known that I, MURRAY HELLER WARREN, a citizen of the United States, residing at the city of Mexico, Mexico, have 5 invented certain new and useful Improvements in Apparatus for Refining Petroleum, of which the following is a specification.

This invention relates to apparatus for refining petroleum.

10 The object of the invention is, in a ready, practical, rapid, and continuous manner, fractionally to distil heavy hydrocarbon oils, to separate the lighter products from the heavier, conserve the former as produced, and present the latter to repeated re-vaporization, whereby substantially the entire bulk of a given charge will be converted into products having any desired specific gravity.

20 With the above and other objects in view, as will appear as the nature of the invention is better understood, the same consists, generally stated, in a refining apparatus embodying a plurality of condensers, a plurality of exchangers, and a plurality of stills, combined with means for supplying oil to the stills in thin sheets or films, and with means for conveying the lighter and heavier products from 25 the stills to the exchangers, whereby the oil contained in the latter will be heated by radiation from the pipes conveying the vapors from the stills, and with condensers through which, by means of 30 suitable conduits, the heated gases or products are led through the condensers, the lighter products being conserved, and the heavier residues being returned for re-vaporization.

35 The invention consists further in the various novel details of construction of an apparatus for vaporizing oil as will be hereinafter fully described and claimed.

40 In the accompanying drawing forming a part of this specification, and in which like characters of reference indicate corresponding parts: Figure 1 is a view in side elevation, partly in section, of one form of apparatus embodying the features of the present invention. Fig. 2 is a sectional detail view of a modified form of a part of the structure. Fig. 3 is a transverse sectional view through a modified form of still.

45 Referring to the drawings, and to Fig. 1 thereof, 1 and 2 designate two condenser casings, 3 and 4 two exchanger casings, and

5 and 6, two still casings or units. These casings may be of any preferred contour in cross-section and will be constructed in such manner as to withstand any degree of pressure to which they may be subjected. 60

Arranged within the stills 5 and 6 is a series of baffles 7 which project from opposite ends of the casing, and terminate short thereof, whereby to impart to the supplied oil a tortuous movement. Communication is established between the two stills by an opening 8 arranged adjacent to one end thereof. As in the operation of the apparatus there might be a tendency for carbon to 70 accumulate on the baffles 7, one end of each of the casings or units is provided with a removable cap 9 which is of a construction commonly employed in structures of this character. 75

As will be obvious, some means should be provided whereby a supply of water may be furnished to the condensers 1 and 2, and in this instance, each of the condenser casings is shown as provided at one end with a 80 valved supply pipe 11 and at its other end with a valved discharge pipe 10 and by this arrangement a fresh supply of water may be fed to the condensers as required.

Arranged in the condenser 1 are two 85 members 12 and 13 of a pipe that is designed to convey the heavy vapors to a suitable point for re-use through the branch 13, the leg 12 having a vertically-extending branch 14, the terminal of which is curved and projects within a trap 15 into which the heavier products are received from the lower still 5 through a coiled pipe 16, two branches 17 and 18 of which are disposed within the ex-changer 4. 90

The condenser 2 has arranged within it two members 19 and 20 of a pipe that is designed to convey light vapors to a suitable point of storage through the branch 20, the leg 19 having a vertically extending branch 21, the terminal of which is curved and projects within a trap 22 into which the lighter products are received from the upper still 6 through a coiled pipe, two branches 23 and 24 of which are disposed within the exchanger 3, the branch 24 entering the trap 22, while the branch 23 projects outward through the head of the ex-changer 3 and extends upward in a vertical branch 25 above the top of the still 6, 110 and is then bent at an obtuse angle to the branch 25 forming a branch 26, the termi-

nal of which is down turned, and enters the still 6 adjacent to what may be termed its rear end. The branch 25 is provided with a valve 27 and the bend between the branches 16 and 17 with a regulating valve 28, and by suitably adjusting these valves, the escape of the lighter and heavier products from the stills to the exchangers and thence to the condensers may readily be controlled.

Disposed adjacent to one end of the apparatus is a pump 29 having combined with it a pressure gage 30 and extending from the pump is a pipe 31 that enters the exchanger 3 adjacent to its bottom, the pump being in connection with a suitable supply of oil for supplying the latter to the exchanger 3, and from the latter through a vertical pipe 34, into the upper exchanger 4. The oil from the upper exchanger is led to the still 6 through a pipe 35 carrying a valve 36 by which the supply may readily be controlled.

In order to effect vaporization of the oil in the stills, it is necessary that superheated steam under high pressure should be supplied thereto, and this is furnished through a pipe 37 carrying a regulating valve 38, the inner end of the pipe being projected into the bottom of the still 5 near its outer end.

As shown in Fig. 1, the baffles 7 are flat plates which are as usual, fixedly secured within the stills, but under some conditions, it may be desired to have the baffles removable in order to permit freeing therefrom of any accumulated carbon deposited thereon from the action of heat. To accomplish this result, the arrangement shown in Fig. 40 is employed wherein the still 39 is shown as provided with a transverse partition 40 arranged on each side of which is a trough 41 and 42 respectively, the sides, 43, of said troughs extending above and below the bed 45 of the trough and arranged on opposite inclines in order to conform somewhat to the cross-sectional area of the still. As shown in Fig. 1, but two stills are employed, but should it be desired to install a series of stills 50 arranged in vertical order, the construction shown in Fig. 2 will be adopted wherein each still is provided with exterior flanges 44 which will form a means of connection with the next adjacent still.

Having described the structure of the apparatus, the manner of its operation will now be explained. Assuming the still to be empty, the pump 29 is started, and the oil is forced into the lower exchanger 3, thence through the pipe 34 to the upper exchanger 4 and thence through the pipe 35 to the upper still 6, where it flows in a thin sheet upon the baffles 7 in opposite directions and escapes through the opening 8 into the lower still 5. When the oil starts to enter the

still, or just prior to its entrance thereto, the valve 38 is opened and superheated steam under high pressure passes through the pipe 37 into the lower still 5, and meets the down-flowing sheets of oil and passes in opposite directions to its movement, and the heat and pressure present will cause fractional distillation of the oil, with the result that the lighter products will pass through the pipe 26, branch 25 and thence into the lower exchanger 3 through the branches 23 and 24 and through the latter into the trap 22. This trap is provided near its bottom with an outlet 45 through which the water of condensation can escape. The vapors rise to the top of the trap and enter the pipe 19 and pass through the branch 20 to a place of storage, the water in the condenser in which the branches 19 and 20 are disposed serving to condense the vapors in a manner that will be obvious. The heavier products enter the branch 16, thence to the branches 17 and 18 within the exchanger 4 and escape through the latter branch to the trap 15, the latter being provided with an escape opening 46 through which the water of condensation may escape. The vapors rise to the top of the trap, enter the branch 14, thence pass to the branches 12 and 13 which are disposed within the condenser 1, and escape from the latter branch to a place of storage whence they may be removed for use, or be returned for re-vaporization. During the procedure the pump is kept constantly working so that the supply of oil to the exchangers will remain constant, thus to maintain an equal temperature therein. The discharge of the products may readily be regulated by the valves 27 and 29, thus to govern the quantities of vapor drawn off, and the length of time the oil is exposed to the destructive action of heat and pressure within the stills for repeated vaporization or cracking. By dividing the oil into small units, the employment of high pressure will be permissible, and in case of rupture of either of the stills, the small quantity of liquid contained within the still combined with the smothering effect of the steam uniting with the vapors will prevent serious accident.

By the foregoing description, it will be seen that although the improvements of this apparatus are comparatively simple in character, they will be thoroughly efficient for accomplishing the object designed and will, in operation, result in the output of the maximum of products in the minimum of time.

What I claim as new is:

1. An apparatus for refining petroleum, comprising a plurality of condensers, a plurality of exchangers, a plurality of communicating stills, a series of longitudinally-dis-

posed baffles within each of said stills, each of which projects from one end of the still and terminates a distance away from the opposite end to provide a tortuous path for the oil, and supply it in thin streams or films, means for supplying oil to the exchangers, means for conveying oil from the exchangers to the stills, means for supplying superheated steam under high pressure to the stills, and means for conveying the lighter and heavier vapors from the stills to the condensers.

2. An apparatus for refining petroleum, comprising a plurality of condensers, a plurality of exchangers, a plurality of communicating stills, a series of longitudinally-disposed baffles within each of said stills, each of which projects from one end of the

still and terminates a distance away from the opposite end to provide a tortuous path 20 for the oil, and supply it in thin streams or films, means for supplying oil to the exchangers, means for conveying oil from the exchangers to the stills, means for supplying superheated steam under high pressure 25 to the stills, means for conveying the lighter and heavier vapors from the stills to the condensers and traps co-acting with the latter means for carrying off the waters of condensation.

In testimony whereof I hereunto affix my signature in presence of two witnesses.

MURRAY H. WARREN.
